(57) **CLAIM**

The ornamental design for an illumination device, as shown and described.

DESCRIPTION

FIG. 1 is a perspective view of an illumination device of the present invention.

FIG. 2 is a front elevational view of the illumination device of FIG. 1.

FIG. 3 is a rear elevational view of the illumination device of FIG. 1.

FIG. 4 is a left-side, elevational view of the illumination device of FIG. 1.

FIG. 5 is a right-side, elevational view of the illumination device of FIG. 1.

FIG. 6 is a top plan view of the illumination device of FIG. 1; and,

FIG. 7 is a bottom plan view of the illumination device of FIG. 1.
